INDUCTIVE-INTERFERENCE PREVENTIVE-MEANS

Lloyd J. Hibbard, Pittsburgh, Pa., assignor to
Westinghouse Electric Corporation, East Pittsburgh, Pa., a corporation of Pennsylvania

Continuation of application Serial No. 113,714,
September 2, 1949. This application October 8,
1949, Serial No. 120,331

25 Claims. (Cl. 307—90)

1

This is a continuation of my application Serial No. 113,714, filed September 2, 1949, now abandoned, under the title, Rectifier Power-Units for Vehicles.

My invention relates broadly to preventive-means for preventing or reducing inductive interference in telephone-lines which are close to alternating-current power-lines in which there are harmonics in the telephone-interference frequency-range. More specifically, my invention relates to a practical and advantageous rectifier-unit for energizing the direct-current series traction-motors of a self-propelled vehicle from a single-phase high-voltage trolley.

A rectifier-powered vehicle of the general type just mentioned was tried out once, on a single railway-car, as described in the Street Railway Journal for December 19, 1914, at page 1343, and also in the Engineer, London, for February 5, 1915, at page 142-143. This car was taken out of service on May 14, 1915, after a 40-day period of operation in 1914, and a 26-day period of operation in 1915. There is evidence that the harmonics in the transmission-circuit for this car caused telephone-disturbances of such serious extent that the entire track-mileage over which the car was operated was equipped with booster-transformers, at frequent intervals, to force the return-currents to flow through the rails, where their inductive-interference effects in adjacent telephone-lines are much smaller than when the return-circuit is through the ground.

Many engineers who are skilled in the rectifier, motor, railway, and inductive-interference arts, all of which are involved, have been opposed, from time to time, to any resumption of work on rectifier-powered vehicles, since that one experiment.

According to one aspect of my invention, when an A.-C. filter is desirable, (which is almost always the case), I use a special capacitor-circuit which is connected across the secondary, rather than across the primary, of the transformer which energizes the rectifiers from the trolley. In this manner I provide a low-impedance circulating path, on the secondary side, for all but the lowest-frequency components of the D.-C. ripple, and I probably also cause these circulated components to flow to some extent non-inductively through the secondary of the transformer. For both of these reasons, very little primary-voltage is available for circulating high-frequency harmonics in the primary circuit of A.-C. supply-line. This secondary connection of the filter-capacitor is, in effect, an anode-to-anode

2

connection, and it is so unconventional that I had to demonstrate that a properly designed anode-to-anode filter-capacitor would work, would be very economical, and would have a number of other important and unanticipated advantages, as will be hereinafter pointed out.

In a rectifier power-unit for the traction-motors of a self-propelled vehicle, the D.-C. output-circuit of the rectifier unit is confined to the vehicle, where there is no inductive-interference problem due to the D.-C. ripple, and hence this D.-C. ripple does not need to be smoothed down to relatively low values, to avoid inductive interference, as has been necessary in D.-C. feeder or trolley-circuits which have heretofore been powered by rectifiers. In such a rectifier-powered vehicle, the entire load on the D.-C. output-circuit of the rectifier-unit consists of the D.-C. traction-motors of the vehicle, and these motors will stand a very substantial ripple while still having black commutation, freedom from objectionable pulsating torque or vibration, and freedom from overheating, as will be subsequently pointed out; and it is an important feature of my invention that I use a fairly large D.-C. ripple.

In carrying out my invention, I also usually put enough inductance in the A.-C. supply-circuit to produce an unusually high angle of overlap or commutating angle of the rectifiers, as will be subsequently explained in detail. The effect of this is to decrease the A.-C. harmonics at the expense of increasing the D.-C. ripple, increasing the regulation, decreasing the power factor, and only very slightly decreasing the efficiency. The D.-C. ripple can be easily controlled by other means, as will be explained hereinafter; and the regulation and the power-factor can both be improved, and restored to something like what they would have been without the increased angle of overlap, by the use of the secondary-connected filter-capacitor which has already been mentioned.

It is also an important feature of my invention, that even though I use voltage-control, I do not do it (to any substantial degree) by delayed firing, or grid-control, or phase-control, as is the universal practice in modern rectifier-systems requiring voltage-control. Delayed firing is an attractive means for obtaining voltage-control for the D.-C. circuit, because its cost is usually less than any tap-changing means for accomplishing the same purpose by changing the transformation-ratio of the transformer which supplies power to the rectifier. However, any considerable amount of delayed firing introduces

a greatly increased inductive-interference problem, and has other disadvantages, as will subsequently be explained, and hence it cannot ordinarily be used in rectifier-powered transportation-equipments in accordance with my invention. I therefore use tap-changing means, to obtain most or all of the voltage-control which may be required in my equipments. For reasons which will be subsequently explained, I preferably use secondary tap-changing, rather than primary tap-changing, so that the transformation-ratio which is applicable to my secondary-connected A.-C. filter (when used) will not be subjected to wide ratio-changes.

As a part of my invention in rare instances, I may use a tuned, second-harmonic filter which is connected across either the motor-armatures, or the entire motor-circuits including armatures, series-field windings and commutating-field windings, and sometimes also across a part of the D.-C. inductance or choke if such an element is used. This expedient, in conjunction with the other features of my invention, enables me to use a rectifier-output having enough ripple so that the A.-C. inductive-interference can be reduced to the necessary level, and if this ripple should be too much for any particular motor-design, its major component (the double-frequency ripple) can be by-passed from the motor by the shunt-connected second-harmonic filter.

An object of my invention is to provide a successful rectifier power-unit for vehicles, embodying one or more of the various novel design-features which have just been briefly outlined, thus combining the advantages of both single-phase trolleys and D.-C. traction-motors, while removing certain previously experienced kw. capacity-limits in self-propelled vehicles, and at the same time reducing the weight, decreasing the cost, and achieving various operational advantages, as will be subsequently pointed out, besides being able to achieve a telephone-interference level which is much lower than has been obtained with single-phase series-motor electrifications.

A more generally stated object of my invention is to apply my novel secondary filter-system to any application where it is necessary, such as an A.-C.-motored railway-vehicle or a polyphase rectifier-system, or, in general, any load-device of a type tending to draw objectionable supply-circuit harmonics in the telephone-interference frequency-range.

With the foregoing and other objects in view, my invention consists of the combination, circuits, systems, parts, and methods of design and operation, hereinafter described and claimed, and illustrated in the accompanying drawing, wherein,

Figure 1 is a diagram of circuits and apparatus illustrative of my invention;

Fig. 2 is a simplified schematic view which will be referred to in the discussion of the A.-C. filter;

Figs. 3 and 4 are portions of oscilloscopic traces illustrating the operation, with the A.-C. filter off and on respectively;

Fig. 5 is another simplified schematic view showing a rectifier bridge which will be referred to in the discussion of my design;

Fig. 6 is a curve-diagram which will be referred to in the discussion of the tuning and the discharge-resistance of the A.-C. filter;

Figs. 7 and 8 are portions of oscillographic

traces illustrating the operation, with the D.-C. filter off and on respectively;

Fig. 9 is a diagram similar to Fig. 1, illustrating my invention as applied to a railway vehicle which is propelled by a series A.-C. motor or motors; and

Figs. 10 and 11 are diagrams illustrative of the application of my invention to polyphase rectifier systems.

- 10 In the typical form of embodiment of my invention, shown in Fig. 1, a high-voltage single-phase trolley is indicated at 1. Single-phase power is supplied to the trolley 1, at various spaced points, such as 2 and 3, from an A.-C. feeder 4 which is supplied with energy from a source or alternator 5. In order to indicate an inductive-interference or telephone-interference problem, I have included, in Fig. 1, a diagrammatic representation of a telephone-system or communication-system 6, which is in proximity to the feeder 4, or the trolley 1, or both.
- 15 The trolley 1 is adapted to supply power to a self-propelled railway-vehicle, which is represented, in Fig. 1, by means of a pantograph 7 and the apparatus which is connected thereto. The pantograph 7 is connected to the high-voltage terminal 8 of the primary winding 9 of a step-down transformer which is provided with an iron core 10 and a secondary winding 11.
- 20 The low-voltage terminal 12 of the primary winding 9 is connected to ground through a primary reactor 13 which is illustrated as being provided with a cut-out switch 14. This primary reactor 13 is provided with an iron core 15 having an air gap.

The secondary winding 11 of the transformer is provided with a mid-tap 16, and it is also provided, at each end, with a plurality of terminal-taps 17, which are engaged by controller-points 40 18 and 19, respectively, which constitute tap-changing means. The mid-tap 16 constitutes the negative terminal of the D.-C. circuit. The two tap-changing terminals 18 and 19 of the secondary winding 11 are connected to the anodes of two rectifiers 21 and 22, the cathodes of which are connected together, to constitute the positive terminal 23 of the D.-C. circuit.

In Fig. 1, the rectifiers 21 and 22 are symbolically indicated, as being any kind of rectifier-means, which, in truth, they may be. For most practical purposes, in the present state of the rectifier-art, these rectifiers will be arcing-type rectifier-tubes, such as ignitrons, or other vapor-rectifiers, mounted either in separate tanks, or both in one tank, and having the well-known characteristic property of single-phase rectifying devices which become substantially non-conducting, once an arc has been established to initiate a conducting period, only in response to a current-decrease to substantially zero.

In accordance with my present invention, these rectifiers 21 and 22 should preferably be rectifiers which do not have any substantial amount of delayed firing, or grid-control, or phase-control, by which I mean anything beyond the amount of delay which would produce a 10% reduction in the D.-C. voltage during maximum line-current conditions, which are obtained while the vehicle is being accelerated. Theoretically, a 25° delay in firing produces a 10% reduction in the D.-C. voltage, and substantially also a 10% reduction in the power factor. In other words, each rectifier, 21 or 22, becomes conductive when its impressed voltage reaches a small value in its conductive polarity. A 10% voltage-reduction, ob-

tained by delayed firing, would possibly cut in half the required number of voltage-changing notches and taps 17 on the controller and on the transfer, and this might be desirable in some cases.

Any increase in the phase-control angle, beyond the amount which would produce about a 10% voltage-reduction, would start to build up the harmonics in both the D.-C. and A.-C. circuits, and would start to reduce the power-factor, both at an extremely fast rate. Since the A.-C. harmonics may create a very formidable inductive-interference problem, and since a poor power-factor may be so serious a handicap as to rule out the rectifier-powered motive-equipment as a practical rival of other available kinds of motive-equipment for vehicles, my present invention usually requires the use of rectifiers which do not have any substantial amount of delayed firing, as has just been defined. When an adequate A.-C. filter 40 is used, however, its beneficial effects on the inductive-interference, the power factor, and the voltage-regulation may sometimes make it feasible to use enough firing-delay to produce the usual 15%, or more, reduction in the D.-C. voltage, by firing-angle control.

The direct-current circuit 23-16 is used to energize the direct-current traction-motor equipment, which is represented for the sake of simplicity, in Fig. 1, as comprising a single motor 24, although it will be understood that usually a self-propelled vehicle will have a plurality of motors, which are commonly connected in some kind of series-circuit arrangement for starting, and in some kind of parallel-circuit arrangement for running conditions. The motor 24 is represented as having an armature 25 and a serially connected commutating-winding 26, which may be connected in the D.-C. circuit 23-16, in either polarity, by means of a reversing-switch 27. The motor also has a series main-field winding 23.

This direct-current motor 24, or any combination of such motors, may be controlled with any of the known forms of speed-control, and I wish, therefore, that the voltage-control method, which is diagrammatically indicated by the tap-controllers 18 and 19, shall be understood as being representative of any suitable or well-known form of motor-control.

The direct-current motor 24 has a certain amount of inductance, which necessarily limits the direct-current ripples to a certain extent. In some cases, for reasons which will be hereinafter discussed, it may be necessary to still further decrease the amount or percentage of the D.-C. ripples, and in such a case, I provide a D.-C. reactor or choke-coil 30, which is connected in series with the motor 24, in the D.-C. circuit. This D.-C. reactor is provided with an iron core 31 having an air gap. It is also shown as being equipped with a short-circuiting or by-passing switch 32, by means of which the D.-C. reactor 30 may be cut out of the motor-circuit 23-16.

In some instances, under unusually critical or difficult design-conditions, it may be necessary, from considerations of telephone-interference due to the harmonics in the A.-C. lines 1 and 4, to cause the D.-C. circuit 23-16 to have a higher percentage or ripple than is desirable in the motor-circuit, including the armature 25, and some of all of the two serially connected windings 26 and 28 thereof. Whenever this is the case, I provide a D.-C. filter-circuit 33, which is by-passed around the desired parts of the motor-circuit, under the control of a switch 34. The D.-C. filter, when it is used, is a tuned filter, com-

prising a capacitor 35 and a serially connected inductor 36, which is shown as having an iron core 37 with an air gap. This tuned D.-C. filter-circuit 33 is tuned approximately to the second harmonic, as will be discussed in detail hereinafter.

In accordance with my invention, it is usually necessary (although perhaps not necessary in every conceivable instance, when the other features of my invention are carefully observed under favorable conditions), to provide an A.-C. filter-circuit 40, which is connected on the secondary side of the transformer, as will be subsequently discussed. This A.-C. filter-circuit 40 is shown, for illustrative purposes, in Fig. 1, as being connected across the terminals S1 and S2 of the secondary winding 11 of the transformer, preferably not across the variable-voltage taps 17 which are used to energize the anode-leads 18 and 19. This connection is intended to be representative of secondary-shunting connections, in general, as will be subsequently pointed out. The A.-C. filter-circuit 40 is an untuned filter, comprising a capacitor C and a discharge-resistance R, preferably connected in series with each other, the details of which will be herein-after discussed in full.

The successful design of a rectifier-powered vehicle in accordance with my present invention involves a consideration of a number of factors, which will now be discussed. Attention will be given, first, to the telephone-interference factor, because this is the factor which, in the minds of most people, has been the stumbling block which has prevented the development of this kind of motive-power for electrified railroad-systems.

I am confident that telephone-interference, in a rectifier-powered railway-vehicle, is not anything like the problem that some people may have assumed it to be. Nevertheless, to get rectifier-powered traction-motor equipments accepted by all parties concerned, it seems to be necessary to give what seems to me to be an exaggerated attention to a far-greater-than-necessary reduction in telephone-interference. After rectifier-powered cars or locomotives have been demonstrated, to everyone's satisfaction, to be capable of economical design so as to have phenomenally low inductive interference with respect to telephone circuits, I expect that some middle ground will be found, in which the many other advantages of my present invention will frequently be far more controlling, in the design, than considerations of inductive interference.

For any given harmonic-distribution in the A.-C. line-currents (including the return-currents), the amount of telephone-interference depends upon the amount of telephone-interference coupling, which, in turn, depends a great deal upon the distribution of the return-currents between the rails and ground; but to an even greater extent it depends upon the nature of the telephone wires and cables, as well as the nearness and the length of their exposure to the trolley-circuits and feeders.

The amount of telephone-interference due to any given harmonic, in a line which is exposed to a certain standardized amount of telephone-interference coupling, is equal to the product of the line-amperes I, times a weighting-factor T which represents the seriousness of the noise-level produced at the frequency of that harmonic, taking into account such factors as coupling, instrument-sensitivity, and human-ear sensitivity, at the various frequencies.

The telephone-interference weighting-factor T is vastly different, for different frequencies, as shown, by a telephone-interference weighting-curve, an approximation of which was published by Barstow et al. in 1935 AIEE, at page 1312, Fig. 6. In a more modern version of this telephone-interference weighting-curve, which is sometimes used, the weighting-factor starts at unity at frequencies of 60 cycles and lower, the presupposed telephone-interference coupling-condition being so chosen that this is so. The weighting-factor reaches $T=2.7$ at 100 cycles, $T=7.6$ at 150 cycles, $T=1000$ at 500 cycles, and rapidly increases up to a maximum of $T=12,100$ at 1070 cycles, after which the weighting-factor T reduces more slowly—to a value of $T=500$ at 4615 cycles, and to still lower values at higher frequencies, with a slight hump from $T=3500$ to $T=3930$ and back again to $T=3500$ at frequencies of 1950, 2950 and 3350 cycles, respectively. The weighting-curve T is still decreasing for frequencies above 4615 cycles, but usually such high harmonics are so small in magnitude that the inductive-interference product IT is quite negligibly small, long before such frequencies are reached.

The total amount of telephone-interference, due to all of the composite frequencies of the line-current, under the previously mentioned standardized telephone-interference coupling conditions, is measured by a so-called telephone-interference factor, called TIF, which is the ratio of the square-root of the sum of the squares of the weighted values, IT , of all of the sine-wave components, including the fundamental as well as the harmonics, divided by the R. M. S. value of the current-wave.

The calculation of TIF, as just defined, has been a standard procedure in previous comparative estimates of the relative telephone-interference effects of different systems. It is based, as has been noted, upon the assumption of a standardized amount of telephone-interference coupling, which is thus a coupling which is constant for all frequencies. The actual noise-level of the telephone-interference has been assumed to be the product of TIF and the A.-C. line current, multiplied by a constant factor representing the actual amount of the telephone-interference coupling.

In a railway-electrification system, however, the assumption of a telephone-interference coupling which is constant for all of the harmonics is not at all true, because the sinusoidal current-components of different frequencies do not divide anywhere near equally between the rails and ground, in returning from the vehicle to the source. This is due to the fact that the rails are made of iron, and thus have a rather considerable inductance, and the rail-impedance is higher for the higher frequencies. As a matter of fact, most of the high-order or high-frequency harmonics return through the ground, while the fundamental wave and the lowest-order harmonics return, to a much greater extent, through the rails. The telephone-interference coupling-factor varies greatly, depending upon the relative distribution of the return-current between the rail and ground. Thus, if all of the return-current passes through the ground, and none of it through the rail, the coupling-factor is about 76 times higher than the coupling-factor which is obtained when all of the current return through the rail.

The thing which controls the acceptability of any distribution-circuit installation is the noise-

level of the telephone-interference during the operating-conditions when the most noise is produced, which, in a rectifier-powered railway-car, means during starting, or during the maximum permissible short-time line-current or loading-conditions. Actually, we are interested in this noise-level and not in any theoretical TIF-calculations which assume a constant, standardized, telephone-interference coupling factor. Actually, therefore, in order to properly evaluate this telephone interference noise-level, we should consider the noise produced by each of the harmonics, by multiplying the value of that harmonic-current by both the weighing-factor T and the particular coupling-factor which is applicable to that harmonic. After making such a calculation, for all of the harmonics having any material magnitude, we could then obtain the telephone-interference noise-factor by calculating the ratio of the square-root of the sum of the squares of these several noise-level products, for all of the harmonics (including the fundamental), and dividing the same by the R. M. S. value of the current.

In the following discussions, I shall refer, in the classical or accepted way, to the telephone-interference factor TIF, which is calculated on the assumption of a coupling-factor which is constant for all of the frequencies. I do this, because this factor is relatively easily calculated, and because so much of the known data is calculated on this basis. This method of estimating the relative telephone-interference merit of my invention is pessimistic or disadvantageous to my invention, however, because, as will be subsequently pointed out, my invention results in a very large reduction in the higher-order harmonics, while accepting large values of the lowest-order harmonics. It will thus be seen that I reduce the noise-producing effects of the higher harmonics, which are the harmonics which are associated with the highest coupling-factors. When my new system is compared, therefore, with other railway-electrification systems, this point should be remembered, namely, that my noise-level is reduced, more than would be expected from a simple comparison of the TIF-values for the different systems, because I so greatly reduce the value of the high-frequency harmonics which do not readily return through the rails.

The maximum R. M. S. line-current (during accelerating-conditions) for a small rectifier motor-equipment of a small multiple-unit car, rated at 460 H. P. (horsepower), at 11 kv. (kilovolts) on the trolley, is something like 75 amperes. On a 5000 H. P. locomotive, operating on a 24 kv. trolley, the maximum R. M. S. line-current (during accelerating-conditions) is something like 400 amperes. This gives some idea of the range of line-currents by which the telephone-interference factor TIF must be multiplied, in order to obtain the relative or comparative total noise-level of the various equipments.

There is evidence that an acceptable type of single-phase series railway-motor (using no rectifiers) has a telephone-interference factor TIF of the order of 27 under maximum-current accelerating-conditions, and something like $TIF=7$ under continuous-load operating conditions.

In a rectifier-powered motor-equipment, most of the telephone-interference comes from the rectification, rather than from the commutator-segments and other factors within the motor

itself. Consequently, I believe that the telephone-interference factor TIF of a rectifier-powered self-propelled vehicle is of the same order of magnitude during accelerating and normal-running conditions, other things being equal.

Without any filter, a rectifier-powered traction-motor which is properly designed and operated in accordance with my invention, with due regard to the magnitude of the D.-C. ripple, the angle of overlap, and the delayed-firing angle, (as will be subsequently explained), will have a telephone-interference factor in the neighborhood of $TIF=80$, or even much less. With a filter in accordance with my invention, the telephone-interference factor TIF may be made as nearly unity as may be desired, economically obtained values of the order of $TIF=7$ being easily feasible.

In a theoretical case, at one extreme, in order to obtain a rippleless D.-C. output-current from a full-wave (bi-phase) single-phase rectifier, such as is shown in Fig. 1, there would have to be an infinite inductance in the D.-C. circuit, there would have to be a zero angle of overlap in the rectifiers and a zero inductance in the A.-C. input-circuit, and the A.-C. input-current would be a square-topped or rectangular wave. It is well-known that a rectangular A.-C. wave having square-topped half-waves can be expressed mathematically by the Fourier series as

$$e = \frac{4E}{\pi} \sum \left(\frac{1}{n} \sin nwt \right) \quad (1)$$

where

e =the instantaneous value of the rectangular wave,

E =the amplitude of the rectangular wave,
 $w=2\pi f$ =the angular velocity of the fundamental wave,

f =the fundamental or line-frequency,

t =time,

n =any odd integer from 1 to infinity.

Thus, a rectangular-wave, 25-cycle, line-current, having an R. M. S. fundamental-frequency current of one ampere, will have a rectangular-wave amplitude of $E=0.25\pi\sqrt{2}=1.111$ amperes, and it will have an infinite number of components, of which the following are exemplary:

Table I.—Components of rectangular A.-C. wave

Harmonic Order n	Frequency f	Amperes	Harmonic Order n	Frequency f	Amperes
1	25	1	23	575	.0135
3	75	.333	25	625	.04
5	125	.2	27	675	.0370
7	175	.1429	29	725	.0314
9	225	.1111	31	775	.0293
11	275	.0909	41	1,025	.0244
13	325	.0769	51	1,275	.01961
15	375	.0667	61	1,525	.01639
17	425	.0588	71	1,775	.01408
19	475	.0526	81	2,025	.01235
21	525	.0476			

The telephone-interference factor TIF of such a wave would be somewhat over

790
1.111 or 710

At the other theoretical extreme, that is, for a pure-resistance load-circuit on the above rectifier, the D.-C. output-current will be half sine waves and the A.-C. input current will be a sine wave, and hence the A.-C. input-current will have no harmonics. It is well-known that a rectified sine wave has an average value $I_0=2I/\pi=0.637I$, where I is the peak value of the sine wave, and

that this rectified sine wave has an infinite number of even harmonics, equal to

$$-2I_0 \sum \left(\frac{\cos mw'}{m^2 - 1} \right)$$

where m is any even integer from 2 to infinity. Defining the percent ripple as one-half of the difference between the maximum and minimum instantaneous values of the D.-C. current wave, divided by one-half of the sum of said maximum and minimum values, for the purposes of the present invention, the percent ripple in a D.-C. wave of such a shape will be

$$(I-0)/(I+0) = \text{unity} = 100\%$$

This gives a telephone-interference factor of $TIF=1$, said factor being due only to the fundamental frequency of the A.-C. line-current.

All practicable rectifier-powered motor-equipments necessarily fall between these two extremes.

One of the first requisites of a successful design, in accordance with my invention, is to use as large a ripple, in the D.-C. circuit 23—16, as can be successfully stood by the D.-C. motor 24, or if, in some extreme case, the motor cannot stand enough ripple to keep the A.-C. supply-circuit harmonics down to a value which will give a satisfactorily low level of telephone-interference, then the D.-C. ripple must be made as high as may be necessary, from the standpoint of the telephone-interference due to the harmonics in the A.-C. supply-circuits 1 and 4, and the excessive ripple-content in the D.-C. motor 24 will have to be bypassed by a D.-C. filter, such as is indicated at 33 in Fig. 1.

Tests have indicated that the curve of TIF, plotted against increasing values of the ripples in the D.-C. circuit, is fairly flat between 25 and 75% ripple, so that any increase in the ripple, about 25 to 30%, is not usually worth while as a means for reducing the telephone-interference which results from the reduced harmonics in the A.-C. supply-line.

The amount of ripple which can be successfully taken or tolerated by the D.-C. motor 24 depends upon whether the motor is a small motor or a large one, a slow-speed motor or a high-speed motor, and on other design-features thereof. The smaller D.-C. traction-motors usually have 4 poles, a series-wound armature, and a solid frame. The large D.-C. traction motors usually have 6 poles, a multiple-wound armature, and may have a laminated frame. A series-wound armature has as many armature-turns, between commutator-bars, as there are pairs of poles, while a multiple-wound armature has only one armature-turn between commutator-bars. The D.-C. component of the motor-current sets up a certain flux-level in the field-circuit of the motor, and the A.-C. ripple-content of the motor-current causes the flux to rise and fall above and below this level. The change in flux, due to this A.-C. component or ripple, sets up certain transformer-volts in each of the armature-turns undergoing commutation. The multiple-wound armature, with only one turn between bars, can thus maintain black commutation with a higher ripple, in the field-flux, than a series-wound armature.

A 30% ripple in a direct-current motor makes very little change in flux under maximum load-conditions, because the motor is operating above the knee of its saturation-curve. At lower motor-current, some considerable sparking would do a negligible amount of harm, because of the smallness of the current. The trouble which results

from a reasonably large amount of ripple in the motor does not come from commutation, but from iron-losses.

The normal D.-C. traction-motor is a solid-frame machine, and if the main-field-flux varies, in this field-frame, it will theoretically produce additional heat. I have tested such traction-motors with rectifier-supplied currents, such as are provided in Fig. 1, and I have found that when the percent ripple is 20 to 25%, the amount of motor-heating, at continuous rating, is not measurably different from the heating which is obtained on pure direct current, without any ripple. If the percentage-ripple were increased to as high as 75%, it is my judgment that special cooling-precautions would have to be taken, for a ripple as high as that, if the motor were a solid-frame motor. If the motor-frame is laminated, the A.-C. ripple-content of the D.-C. current would not cause any undue heating, even at these larger values.

The flux-pulsations, due to the ripple in the motor-current, cause corresponding pulsations in the motor-torque, resulting in a certain amount of vibration of the motor. There is a scarcely detectable amount of increased vibration of the motor, when the ripple is changed from 5 to 25%. When the ripple is still further increased, say from 25 to 75%, the increase in motor-vibration is quite noticeable, although it would probably be acceptable, so far as vibration is concerned, even at the 75% ripple-level, if other things were satisfactory. In other words the D.-C. traction-motor, when powered from a rectifier would not need to be equipped with flexible gears (not shown), such as are always required by A.-C. traction-motors, even when the D.-C. motor has a 75% ripple in its current.

In general, in accordance with one aspect of my preferred embodiment, it may be stated that the total inductance of the direct-current circuit 23-16 should be sufficiently small to permit at least a 25% ripple to be present during maximum short-time load-conditions such as during acceleration; although in some cases a 20% ripple might be regarded as the minimum desirable value, or even the usual 15% ripple, which may sometimes be tolerated in the D.-C. circuit 23-16 during the maximum short-time load-conditions.

If the second harmonic of the input-circuit frequency is by-passed around the motor-winding, as when the D.-C. filter-circuit 33 is used, the higher even harmonics are the only harmonics left in the motor-circuit, and these are unimportant for two reasons: first, the magnitudes of the harmonics are inversely proportional to their orders, so that the fourth harmonic, for example, is only one-half as large as the second, and so on; and secondly, the impedance of the reactance in the D.-C. circuit, including the D.-C. choke-coil (if any), increases in direct proportion to the order of the harmonic, so that this impedance is twice as great for the fourth harmonic (for example) as it is for the second harmonic, and so on. The higher even harmonics rapidly disappear, and they do not ordinarily produce sufficient ripple in the D.-C. motor-current to be of any practical consequence in a rectifier powered self-propelled vehicle.

The angle of overlap, or commutating angle, of the rectifiers 21 and 22 has an unexpectedly important effect upon the amount of inductive-interference which is obtained from the A.-C. supply-circuits which supply a rectifier-powered traction-motor equipment of a railway-vehicle.

The angle of overlap of a two-phase rectifier, such as that shown in Fig. 1, is a function of a commutation-factor which is equal to the magnitude of the direct-current which is being commutated or transferred from one rectifier-circuit to the other, multiplied by the supply-circuit inductance up to the rectifiers 21 and 22, this inductance being the equivalent secondary-circuit inductance L of the transformer and of the entire supply-circuit back of the transformer, as seen from the secondary terminals, this product being divided by the secondary voltage. The angle of overlap is increased when the effective transformer-inductance L is increased.

If the angle of overlap, or commutating angle, is increased, the A.-C. harmonics in the line-current begin to be reduced, rapidly at first, but by the time the angle of overlap reaches 40°, or between 35° and 45°, the slopes of the harmonic-curves level off, so that further increases in the angle of overlap yield too small a benefit, in the form of reduced A.-C. harmonics, to warrant the expense of the necessary primary or transformer-inductance, or the consequent disadvantages in the way of poorer regulation, lower power-factor, and less efficiency. I prefer to use about a 40° angle of overlap, or say between 35° and 45°, during vehicle-accelerating load-conditions, or maximum short-time line-current or load-conditions, which are the severest conditions from the standpoint of inductive-interference. During continuous-rating line-current or load-conditions, when both the motor-current and the line-current may be about 50% of the maximum current during acceleration, the reduction in the line-current causes the angle of overlap to be reduced to something like 25° to 30°. In the power-rectifier practice prior to my invention, the maximum angle of overlap has been about 20° to 25°. I prefer to make 20° to 25° the minimum angle of overlap which I ever use under maximum-current conditions.

In general, in accordance with one aspect of my invention, I prefer to include, in my primary circuit 5-4-2-1-9-13, sufficient inductance to cause the conducting-periods of successively operating rectifiers to overlap for at least about 20° during each half-cycle, during maximum short-time line-current or load-conditions, such as during acceleration.

My higher-than-usual angle of overlap also increases the D.-C. harmonics, but, as I have already pointed out, the motor 24 can, in general, stand the increased D.-C. harmonics, and in the relatively small number of cases when this may not be so, the second harmonics, which are the largest harmonics of the D.-C. circuit, can be bypassed out of the motor by means of the D.-C. filter 33.

To give some indication as to the effect of the angle of overlap on the direct-current voltage, it may be noted that a 25° to 31° commutation-angle, with no delayed firing, produces a 6% to 8% regulation.

It has been noted that an increase in the angle of overlap carries with it an increase in the amount of voltage-drop or regulation in the D.-C. voltage, and a decrease in the power factor of the A.-C. current which is drawn from the line. The application of the secondary-filter 40, with its really considerable leading kva., makes it possible to work at higher angles of overlap than might otherwise be acceptable from the standpoint of power factor. This same leading kva., drawn through the reactance of the

power-supply system (including the transformer), as seen from the terminals of the filter, increases the A.-C. voltage and hence the D.-C. voltage, thus making it possible to use a higher A.-C. reactance, and thus to work at a higher angle of overlap, than might otherwise be acceptable from the standpoint of regulation. It is desirable to have some droop, or regulation, in the D.-C. voltage-curve, in order to keep the number of speed-controlling or accelerating notches to a reasonable number, but, on the other hand, too much regulation might be undesirable, in requiring the addition of too many turns on the transformer-secondary, and too high a low-load secondary-voltage in order to maintain the desired voltage during the accelerating period.

The use of an uncommonly large angle of overlap, in accordance with my invention, involves the use of an uncommonly large amount of equivalent secondary-circuit inductance L of the combined transformer and supply-system, that is, the inductance as seen from the secondary side. This means, either the use of a large primary-circuit inductance 13 , in series with the supply-line, or, what is usually more economical, the building of an unusually large amount of leakage-inductance into the transformer 10 , so that the primary-circuit inductance 13 can be omitted, or by-passed by the closure of the cutout switch 14 .

The primary-circuit inductance could be increased, as by a manipulation of the switch 14 , during line-circuit load-conditions which are lighter than maximum starting-conditions, so as to prevent the commutating angle, or angle of overlap, from decreasing when the line-current decreases. When the commutating angle decreases, the telephone-interference factor TIF increases, but the total telephone-interference is the product of TIF and the line-current, so that, in general, any increase in TIF, when the line-current decreases, does not increase the noise-level of the telephone-interference.

The effect of the secondary-connected A.-C. filter 40 , with all of its ramifications, is somewhat difficult to grasp, even on a qualitative basis; and it is practically impossible to pre-calculate, on an exact mathematical basis, without the use of empirically obtained values of the constants. An approximately equivalent circuit for the transformer-secondary, the rectifier, and the D.-C. circuit is shown in Fig. 2, corresponding approximately to Fig. 1, and using the same reference-numerals. One of the difficulties is to determine the proper value of the effective secondary inductance to be applied to the two secondary halves or to the whole of the secondary winding 11 , and the proper value of the mutual inductance between the two secondary halves.

In Fig. 2, the current-flow is shown at an instant when the upper rectifier 22 is carrying a current I , and when the other rectifier 21 is carrying no current. This current I flows from the transformer-terminal 19 , through the rectifier 22 to the positive D.-C. terminal 23 , and thence through the D.-C. reactor 39 and the D.-C. motor 24 to the negative D.-C. terminal 16 , which is the mid-point of the transformer secondary-winding 11 . At this point, the current divides. A major portion, I' , of the current flows through the upper secondary-half, from the mid-point 16 to the upper terminal 19 , because the polarity of the line-frequency secondary voltage is such that the upper terminal 19 is positive with respect to the mid-point 16 , and

the mid-point 16 is positive with respect to the lower terminal 12 . However, there is presumably a certain small current-component, in one direction or the other, flowing in the circuit from the mid-point 16 through the bottom half of the transformer-secondary to the lower terminal 18 , and through the filter-circuit 40 back to the upper terminal 19 , as indicated by the arrow I'' in Fig. 2.

10 The circuit-constants for this circuit vary, with each frequency of the harmonic or ripple content of the main current I , so that, in reality, a separate equivalent-circuit diagram would have to be set up for each harmonic, replacing the conducting rectifier 22 with an equivalent impedance, and omitting the non-conducting rectifier 21 altogether. There are two transformer-voltages, which are produced in the lower secondary-half between the points 16 and 18 , at 15 any harmonic-frequency. One of these transformer-voltages is an odd-harmonic voltage, which is induced by the corresponding odd harmonic of the current in the transformer, and which is in the same polarity throughout the 20 entire secondary winding 11 , so that, if the polarity of the upper terminal 19 of the top secondary-half is positive, for this transformer-induced odd-harmonic voltage, at any instant, the polarity of the mid-point 16 , which is the upper terminal 25 of the lower secondary-half, is also positive for 30 that secondary-half at the same instant. Besides this voltage, there is a balance-coil voltage, which is produced by the mutual impedance between the two halves of the transformer-secondary 11 , and which has a tendency to make the current I which enters at the mid-point 16 divide equally, so that it goes in opposite directions, upwardly in the upper winding-half, and downwardly in the lower winding-half.

40 The effective inductance of the lower winding-half, if that can be estimated, is to be added to the filter-circuit impedance of the capacitor C and the resistance R , to determine the direction and phase and magnitude of the current I'' of the lower winding-half, whereas the phase and magnitude of the main divided current I' , in the upper winding-half is dependent only upon the effective inductance of that winding-half (if it can be estimated), and the resultant of the transformer-induced voltages.

45 The explanation just given assumes that the harmonics involved are the odd harmonics, which are the harmonics which are present in the primary circuit of the transformer. In the D.-C. circuit, however, the harmonics which are present as ripples in the actual direct current I are even harmonics. The odd harmonics are obtained in the process of rectification, as will be mentioned later on, but this rectification-process occurs during each half-cycle of the fundamental wave of the primary-circuit supply. Furthermore, the effect of the filter-capacitor C cannot be properly evaluated, in any equivalent A.-C. circuit, because this filter-capacitor C is short-circuited, and completely discharges itself, during each commutating-period, that is, twice during each line-frequency cycle, as will now be discussed.

50 During the commutating period, when both rectifiers 21 and 22 are carrying current, in Figs. 1 and 2, the total secondary voltage, across the terminals 18 and 19 , is practically zero, being the sum of the voltage-drops in the two rectifiers, under the current-conditions prevailing in the respective rectifiers. This means that the filter-75 capacitor C is practically short-circuited during

this commutating period, so that it becomes completely discharged, its discharge-circuit being through the anode-lead 18, the rectifier 21, the common cathode-circuit 23, the rectifier 22, the anode-lead 19, and the discharge-resistor R, back to the capacitor C. The inductance L_D of this discharge-circuit is very small, being practically the inductance of the leads. In one particular case, this discharge-circuit inductance has been estimated at $L_D = .00006$ henry. If the discharge-resistance R is smaller than the critical resistance for this discharge-circuit containing the capacitance C and the inductance L_D , then the discharge of the capacitor, during each commutating-period, will be oscillatory, at a high frequency dependent upon the product CL_D . If the discharge-resistance R is equal to, or larger than, the critical value, the capacitor-discharge will be non-oscillatory.

A circuit which would be somewhat easier to analyze, than Fig. 2, would be a bridge-rectifier circuit, as shown in Fig. 5, in which the transformer-secondary winding 11' has substantially the same number of turns as only half of the transformer-winding 11 in Fig. 1 or in Fig. 2. In Fig. 5, the two previously described rectifiers 21 and 22, are replaced by four bridge-connected rectifiers 22', 21', 22'' and 21'', arranged to receive secondary voltage from the terminals 19' and 18' and to deliver D.-C. voltage to the terminals 23' and 16', so as to energize the motor 24 with rectified current. In Fig. 5, at an instant when the upper terminal 19' is positive, the current I is supplied from this terminal 19', through the rectifier 22', to the D.-C. circuit 23'-16', and thence through the rectifier 22'' to the other secondary terminal 18'.

It is usually considered that, from a rectifier standpoint, the bridge-rectifier circuit of Fig. 5 is equivalent to the half-wave rectifier-circuit of Fig. 2, but this equivalency of the two circuits has previously been considered without reference to the effect of the filter-circuit 40 which I have added. One practical difference between the two circuits is that the bridge-circuit of Fig. 5 dispenses with the necessity for using one-half of the transformer-secondary which has to be supplied with Figs. 1 and 2, but this advantage in the transformer-cost is obtained at the expense of requiring twice as many rectifier-tanks, besides doubling the rectifier-losses, and in practical circuits and rectifier-tanks are much more costly than the secondary-winding turns, so that the double-wave rectifier-circuits of Figs. 1 and 2 are much more economical.

If we neglect the effect of the angle of overlap, which discharges the filter-capacitor C twice during each line-frequency cycle, we can calculate the effect of the A.-C. filter 40 in the bridge-circuit of Fig. 5.

I first consider the bridge-type rectifier, because it is easier to analyze for harmonics. I first assume that a certain magnitude of a particular harmonic-current I_x is present in the secondary current of the transformer. Then, without my secondary filter, and assuming a negligible magnetizing current of the transformer, the magnitude of the (secondary-voltage-base) transformer-voltage which is produced by said secondary harmonic I_x is simply the impedance-drop in the equivalent supply-circuit inductance L, which is the inductance of the transformer and primary supply-circuit combined, as seen from the secondary side, or

$$E_L = wLI_x$$

If now, we add the secondary filter-capacitor C, with its serially connected damping-resistance R, as shown in Fig. 5, the voltage which is required to maintain the same current-harmonic I_x in the input-circuit of the rectifier-bridge will be

$$\dot{E}_{LC} = \frac{I_x}{\frac{1}{jwL} + \frac{1}{R - j/wC}} = \frac{jwLI_x(R - j/wC)}{R + jwL - j/wC} \quad (3)$$

The magnitude of this transformer-voltage, with the filter in use, is

$$E_{LC} = wLI_x \sqrt{\frac{R^2 + 1/w^2C^2}{R^2 + (wL - 1/wC)^2}} \quad (4)$$

The effect of adding the filter, therefore, (still assuming that the bridge-input current-harmonic I_x is fixed by the D.-C. output-circuit of the bridge), is to multiply the previous transformer-voltage E_L by a factor K which is

$$K = \frac{E_{LC}}{E_L} = \sqrt{\frac{R^2 + 1/w^2C^2}{R^2 + (wL - 1/wC)^2}} \quad (5)$$

If we put w_0 for the angular velocity $2\pi f_0$ of the parallel-resonant frequency f_0 of the filter-capacitance C with respect to the supply-line inductance L, up to the filter-terminals, we may replace the capacitance C by

$$C = 1/w_0^2 L \quad (6)$$

yielding

$$K^2 = \frac{R^2 + \frac{w_0^4}{w^2} L^2}{R^2 + \left(wL - \frac{w_0^2}{w} L\right)^2} = \frac{R^2 + \frac{w_0^4}{w^2} L^2}{R^2 + \frac{w_0^4}{w^2} L^2 \left(\frac{w^2}{w_0^2} - 1\right)^2} \quad (7)$$

If we now assume that the discharge-circuit has an inductance L_D of .00006 henry, and that the discharge-resistance R has its critical value, then

$$R^2 = \frac{4L_D}{C} = \frac{.00024}{C} = .00024w_0^2 L \quad (8)$$

yielding

$$K^2 = \frac{.00024w_0^2 L + \frac{w_0^4}{w^2} L^2}{.00024w_0^2 L + \frac{w_0^4}{w^2} L^2 \left(\frac{w^2}{w_0^2} - 1\right)^2} = \frac{.00024 + \frac{w_0^2}{w^2} L}{.00024 + \frac{w_0^2}{w^2} L \left(\frac{w^2}{w_0^2} - 1\right)^2} \quad (9)$$

The value of the multiplying-factor at resonance is seen, from Equations 5 and 7, to be

$$K_0 = \sqrt{\frac{R^2 + 1/w_0^2 C^2}{R^2}} = \sqrt{\frac{R^2 + w_0^2 L^2}{R^2}} \quad (10)$$

becoming smaller with an increase in the discharge-resistance R.

If we assume that the discharge-circuit inductance is $L_D = .00006$, and that the discharge-resistance has its critical value, as stated in Equation 8, then the value of the multiplying-factor at resonance becomes

$$K_D = \sqrt{\frac{4L_D + L}{4L_D}} = \sqrt{\frac{.00024 + L}{.00024}} \quad (11)$$

being independent of the resonant frequency f_0 , and becoming larger with an increase in the equivalent feeder-and-transformer inductance L, as seen from the secondary side, but becoming smaller with an increase in the extremely small discharge-circuit inductance L_D .

In the curve-diagram of Fig. 6, I have plotted the calculated values of the multiplying-factor K against the frequency, using Equation 9, thus assuming, with Equation 9, a critical value of the discharge-resistance R , and further assuming three different transformers, having equivalent secondary inductances (including the supply-system) as follows,

$$\begin{aligned} L_1 &= .004 \\ L_2 &= .005 \\ L_3 &= .006 \end{aligned} \quad (12)$$

We then have the following three equations,

$$\left. \begin{aligned} K_1^2 &= \frac{.24 + \frac{4w_0^2}{w^2}}{.24 + \frac{4w_0^2}{w^2} \left(\frac{w^2}{w_0^2} - 1 \right)^2} \\ K_2^2 &= \frac{.24 + \frac{5w_0^2}{w^2}}{.24 + \frac{5w_0^2}{w^2} \left(\frac{w^2}{w_0^2} - 1 \right)^2} \\ K_3^2 &= \frac{.24 + \frac{6w_0^2}{w^2}}{.24 + \frac{6w_0^2}{w^2} \left(\frac{w^2}{w_0^2} - 1 \right)^2} \end{aligned} \right\} \quad (13)$$

In each case, I have assumed three different parallel-resonant frequencies,

$$\begin{aligned} f_1 &= 100 \\ f_2 &= 200 \\ f_3 &= 400 \end{aligned} \quad (14)$$

In Fig. 6, the three curves for a resonant-frequency of 100 cycles, are shown at 41₄, 41₅ and 41₆, respectively, the subscripts indicating the assumed equivalent secondary inductance L , in milli-henrys. As was to be expected from Equation 11, the maximum value of the multiplying-factor K , which occurs at the resonant frequency, increases when the equivalent secondary inductance L is increased. The corresponding curves for resonant-frequencies of 200 and 400 cycles, respectively are shown at 42₄, 42₅, 42₆ and 44₄, 44₅, 44₆, respectively. As was also to be expected from Equation 11, when the inductance L is held constant, and the magnitude of the filter-capacitor C is changed in order to change the resonant-frequency, still keeping the discharge-resistance R unchanged at its critical value, the maximum value of the multiplying-factor K remains unchanged, as will be seen by comparing curves 41₄, 42₄ and 44₄.

In Fig. 6, I have also plotted two other curves, numbered 45₂ and 45_c, respectively, showing the calculated effect of using discharge-resistances R of different magnitudes, assuming, for this purpose, a discharge-capacitor C having a capacitance of .00012 farad, with a transformer, as shown in Fig. 1, having an open-circuit voltage of 2344 on the primary winding 3, and 1330 on the total secondary winding 11, with a 25-cycle supply-line. The 25-cycle reactance of the primary circuit, including the transformer 10, the A.-C. supply-lines 1 and 4, and the source 5, is 5.59 ohms on the primary-voltage base. The A.-C. reactance, on the secondary-voltage base, is

$$\left(\frac{1330}{2344} \right)^2 \times 5.59 = 1.800 \text{ ohms at 25 cycles.}$$

The harmonic-order at which the filter-capacitor C is tuned is

$$\sqrt{\frac{1}{1.8 \times .006\pi}} = 5.429$$

and the parallel-resonant frequency is

$$f_0 = 5.429 \times 25 = 135.7 \text{ cycles}$$

The equivalent secondary-circuit inductance of this transformer, for curves 45₂ and 45_c, is

$$L = \frac{1.800}{50\pi} = .011457 \text{ henrys} \quad (15)$$

In Fig. 6, the curve 45₂ is calculated for a discharge-resistance R having a value of 2.084 ohms. From Equation 5, the multiplying-factor for the various harmonics, as a result of adding the filter-capacitance $C = .00012$ and the discharge-resistance $R = 2.084$, is found to be

$$K = \sqrt{\frac{4.34 + \frac{1759000}{f^2}}{4.34 + \left(.07199f - \frac{1326.3}{f} \right)^2}} \quad (16)$$

Curve 45_c is plotted from this equation.

The critical value of the discharge-resistance, if the assumed value of the discharge-inductance $L_D = .00006$ is correct, would have been

$$R_c = \sqrt{\frac{.00024}{.00012}} = \sqrt{2} = 1.414 \text{ ohms} \quad (17)$$

and with this critical value of discharge-resistance, the multiplying-factor would have been

$$K_c = \sqrt{\frac{2 + \frac{1759000}{f^2}}{2 + \left(.07199f - \frac{1326.3}{f} \right)^2}} \quad (18)$$

Curve 45_c is plotted from this equation.

It will be seen, from curves 45₂ and 45_c, in Fig. 6, that the effect of using discharge-resistances R of different magnitudes is as was to be anticipated from Equation 10, namely that the peak of the multiplying-factor K , at resonance, becomes smaller when the discharge-resistance R is increased.

It will be noted that I started out by plotting curves 41, 42 and 44, with their various subscripts, using equations which were calculated for a bridge-rectifier circuit, as shown in Fig. 5, and then I used the same formulas as if they applied to a double-wave rectifier-circuit such as is shown in Fig. 1 or Fig. 2, because curves 45₂ and 45_c were plotted for the type of rectifier-connection which is shown in Fig. 1. In so applying the formulas, I have neglected the effect of the short-circuiting of the filter-capacitor C during the commutation period, as already pointed out; and I have also ignored the almost insuperable problems relative to the partially non-inductive division of the D.-C. harmonics in the two halves of the secondary winding 11 in Fig. 2, and also the well-nigh insuperable problem of converting the rectified even-numbered harmonics of the D.-C. circuit into the equivalent odd-numbered harmonics in the supply-lines 1 and 4, with any kind of regard to the relative lengths of the power-transfer periods and the commutating periods of the rectifiers. I have also calculated the capacitance C and the secondary inductance L on the basis of the same secondary volts, which, of course, is proper.

To indicate how accurately the formulas apply to the circuits shown in Figs. 1 and 2, I have added, to curve 45₂, in Fig. 6, an indication of

the actual values of the multiplying-factor K , which were obtained at different odd-numbered harmonics of the line-current, these actual values being indicated by small circles drawn on the diagram. There appear to be two respects in which the double-wave rectifier, with a mid-tapped secondary, as shown in Fig. 1, departs from the theoretical formulas for the bridge-rectifier circuit of Fig. 5. Apparently, the periodic short-circuiting of the filter-capacitor, during the commutating periods in Fig. 1, makes the circuit operate, particularly in the vicinity of the resonant frequency and at lower frequencies, as if the capacitor were slightly smaller than it actually is, this effect being indicated by the apparent shifting of the resonant-frequency to a slightly higher value than the calculated value.

A second respect in which the actual values obtained for Fig. 1 depart from the values which were calculated from the formula, as shown in curve 45₂ of Fig. 6, is to apparently somewhat reduce the peak of the resonance-curve from the value which is shown for the calculated curve 45₂ in Fig. 6. I believe that this effect is due to the changes in the current-division which was discussed in connection with Fig. 2 and the divided currents I' and I'' which flow in apparently opposite directions in the two halves of the transformer-secondary. At the higher frequencies, the voltage-drop across the filter-capacitor C approaches very small values, so that the two secondary terminals 18 and 19 in Fig. 2 are practically short-circuited by the filter-capacitor C , for harmonics of high orders. This short-circuiting effect at high harmonics or frequencies would not have been obtained if the filter-circuit 40 had been tuned, that is, if it had contained any substantial amount of inductance in series with the capacitor C and the resistor R .

At lower frequencies, the impedance-drop across the capacitor C , in series with the equivalent inductance of one-half of the transformer-secondary, has a finite value, and varies in both magnitude and sign (or phase), with different low frequencies. These effects are practically impossible to precalculate, with any degree of accuracy. Fortunately, the effects are favorable to the circuits shown in Figs. 1 and 2, in apparently reducing the sharpness of the peak which represents the maximum value of the multiplying-factor K by which the low-frequency harmonics are multiplied, as a result of adding the A.-C. filter-circuit 40 in Fig. 1.

A better insight into the operation of my invention will be had by a study of the reproductions of oscillographic records which have been made, as shown in Figs. 3, 4, 7 and 8.

Figs. 3 and 4 show the results, first without the A.-C. filter 40 of Fig. 1 (in Fig. 3), and then the results obtained with the filter connected (in Fig. 4). The apparatus used for these oscillograms was the same as that for which curve 45₂ was drawn in Fig. 6, except that the discharge-resistance R had a value of 1.063 ohms, instead of the value 2.084 ohms, which was the case for said curve 45₂. The discharge-resistor value $R=1.063$ is thus less than the calculated critical value of discharge-resistance, which has been shown to be $R_c=1.414$ ohms, as shown in Equation 17, and hence the capacitor-discharge, during the commutating period, should be oscillatory, as indeed it was, as shown in Fig. 4, as will be pointed out directly.

Figs. 3 and 4 each show four simultaneously obtained traces, showing relative phase-positions

5 of line-current (or the current in the primary lead 12); the A.-C. filter-current (or the current in the filter-circuit 40); the secondary voltage (appearing across the terminals 18 and 19); and finally the combined anode-currents (or the currents in the two anode-leads 18 and 19). The overlap-period or commutating angle is shown by the zero values of the secondary voltage, one such period extending from a to b in each of said Figs. 3 and 4. It will be noted that the filter-current is zero, in Fig. 3, because the filter is off or disconnected. In Fig. 4, it will be noted that the discharge-current of the filter-capacitor, at the beginning of each commutating period ab , is oscillatory, as indicated by the change in the polarity or direction of the filter-current before it subsides to zero, during this commutation-period. This discharging-period of the filter-capacitor extends from a to c in Fig. 4. It will be noted that the filter is inactive during the rest of the commutating period, that is, from c to b , and then the filter becomes active again during the energy-transfer periods of the respective rectifiers, as from b to d in Fig. 4.

20 The effect of the A.-C. filter, in magnifying or enlarging the low-frequency harmonics, in both the A.-C. line-current and the D.-C. current (which is a rectification of the anode-current), is plainly shown in Figs. 3 and 4. In fact, the 25 shape of the line-current, in Fig. 4, with the filter on, looks, to the eye, much worse than the shape of the line-current in Fig. 3, with the filter off. This is because the low odd harmonics, which are readily detected by the eye, are actually worse in Fig. 4 than in Fig. 3, but the high-frequency harmonics, which can be properly evaluated only by meticulously careful analysis, fall off very rapidly, in Fig. 4, as the harmonic-order increases, so that these harmonics practically vanish, at orders of about the 39th, corresponding to 795 cycles on a 25-cycle supply-line.

30 Herein lies the explanation of the efficacy of my A.-C. filter-circuit 40, namely that it strongly and powerfully suppresses the harmonics of the A.-C. line-current, starting at a frequency not greatly above the resonance-frequency of the filter. This is important, from a telephone-interference standpoint, because of the extremely rapid rate at which the value of the interference weighting-factor T increases, particularly in the frequency-range from say about 200 cycles, where $T=16$, to 1070 cycles, where $T=12,100$.

35 The effect of the omission or inclusion of the D.-C. filter-circuit 33 is illustrated in Figs. 7 and 8, which give portions of simultaneous oscillographic traces showing the relative phases of the D.-C. filter-current (in the circuit 33), and the motor-current I_{de} (in the circuit 25-26-27). In Fig. 7, the D.-C. filter was off, so that the filter-current was zero, and it will be seen that the 40 percent ripple in the motor-current was 29%. In Fig. 8, the D.-C. filter was connected in circuit, in parallel to the motor, and it will be seen that the filter draws a practically sinusoidal double-frequency current, and that the percent ripple in the motor-current is thereby reduced to 9%. This reduction is brought about, because the second harmonic is much the largest of all of the harmonics in the D.-C. circuit 23-16, and when this harmonic is removed, the D.-C. ripple is always reduced to relatively low values, as has previously been discussed. The commutating period in Figs. 7 and 8 has been indicated by the vertical lines a and b , as in Figs. 3 and 4.

It will be noted that the percentage ripple in Fig. 7, without the use of the D.-C. filter, was quite within the usually acceptable limits, which have been indicated as approximately between 25% and 30%. Some motors may take a 40% ripple, or even up to the vicinity of 75% ripple, without undue distress, whereas, in other cases, where the motor-design is more critical, in one way or another, a ripple of less than 25% may be required, as has previously been indicated. The tuned D.-C. filter 33, as shown in Fig. 1, and as shown by the comparison of Figs. 7 and 8, provides a means whereby this D.-C. ripple can easily be reduced to any value which may be required by the particular type of direct-current motor 24 which is used, while at the same time permitting the overall ripple, in the D.-C. circuit 23-10, to have as large a value as may be necessitated from the standpoint of an acceptable inductive telephone-interference factor TIF.

It seems to be necessary, or at least extremely important, that the D.-C. filter 33 should be a tuned filter, including an inductance 36 as well as a capacitance 35, as distinguished from the A.-C. filter 49, which is untuned, in the sense that it has a capacitance C but substantially no inductance included in the filter-circuit 40. I have tried using an untuned D.-C. filter, consisting simply of a capacitor 35, without an inductance 36, in accordance with a previously known practice of shunting the output-circuit of a rectifier with a filter-capacitor for smoothing out the ripples in the D.-C. voltage, and I have found that I invariably ran into difficulty, when the load-circuit on the rectifier consisted of a highly inductive motor-circuit, as in the present instance, because a ripple-smoothing filter-capacitor 35, when used alone, that is, untuned, without any substantial inductance in series with it, would invariably or frequently resonate in parallel-resonance with the parallel-connected motor-inductance at some harmonic-frequency, thereby producing undesirable effects.

In the usual practice of my invention, the A.-C. supply-circuit will be given a certain amount of inductance, which is usually most economically built into the transformer 10, which will produce a larger-than-usual angle of overlap, or commutating angle, of the rectifiers, as has previously been discussed, while the D.-C. circuit 23-10 will usually be designed with a smaller-than-usual inductance (including the inductance of the motor itself, plus the inductance of any serially added inductor 36 which may be used). In general, it will be found economical to operate the motor with as high a percentage of ripple as the motor will take, without undue distress, and in some cases, if the motor is rather unusually sensitive to ripples, it may be necessary, from the standpoint of telephone-interference, to provide the overall D.-C. circuit 23-10 with more ripple than the motor can take, and to remove the excess ripple from the motor-circuit by means of the second-harmonic D.-C. filter 33.

With the two above-stated design-features, namely a high primary inductance (or a high supply-circuit inductance up to the rectifiers, which causes a large angle of overlap) and a small D.-C. inductance (or high ripple-percentage), I believe that the telephone-interference factor TIF will frequently be found to be within acceptable limits, but whenever this is not so, my A.-C. filter 40 provides a means whereby the telephone-interference factor TIF may be eco-

nomically reduced to any value which may be required.

The importance and the advantages of my anode-to-anode, or secondary-connected A.-C. filter 40 are so great, however, that I believe that this filter will usually be advantageously used, even when it is not required from the standpoint of reducing telephone-interference. I believe it to be an important part of my invention to use this A.-C. filter, even aside from strict adherence to the preferable limits regarding the commutating angle and the D.-C. ripple, and even regardless of telephone-interference requirements. Some of the advantages of the A.-C. filter 40 may be briefly indicated as follows.

The anode-to-anode or secondary-connected filter 40 delays the building up of the anode-voltage at the beginning of each conducting-period, while the filter-capacitor is charging, as shown at 46 in Fig. 4, thereby allowing more deionizing time, which reduces backfires to an extent which is almost unprecedented in rectifier-practice.

I have found that the required A.-C. filter 40, for reducing the A.-C. harmonics, is so much more effective, on the secondary side rather than the primary side of the transformer (particularly when a high supply-circuit reactance is used, and built into the transformer), that a secondary filter-capacitor of only one-sixth the size would do the work of a given primary filter-capacitor. There are several reasons for this.

In the first place, the cause of the A.-C. line-current harmonics is the rectified difference-ripples which result from the reduction of the D.-C. ripple from the theoretical ripple-content of a rectified sine-wave; that is, the rectified difference between the theoretical ripple-content of the D.-C. load-current, plus any A.-C. input-harmonics that are caused by or during the commutating-angle. These difference-ripples in the D.-C. circuit are rectified by the two rectifiers in such a manner that a polarity-reversal of the difference-ripple occurs, not at each half-cycle of each of the component ripple-frequencies, but at each half-cycle of the primary wave, or during the respective conducting-periods of the two rectifiers. The harmonics in the A.-C. secondary current in the output-leads 18 and 19 of the transformer result from a Fourier-series analysis of these rectified difference-ripples.

If a low-impedance filter-path 43 for these rectified difference-ripples is provided in shunt relation to the secondary side of the transformer, then the only harmonic-voltage which is built up in the transformer is the voltage-drop due to the flow of these rectified difference-ripples through the small impedance of this filter-path 40. This path has a lower impedance than would be provided by any primary-side filter, because then the harmonics due to the rectified difference-ripples would have to pass through the inductance of the transformer before reaching a primary filter-capacitor, and the total impedance of the filter-path would be much greater than that of the secondary filter. Furthermore, when the filter-capacitor is placed across the secondary side of the transformer, the inductance of the transformer acts as a buffer between the filter-voltage and the line-currents, thus reducing the magnitude of the harmonics which are circulated in the A.-C. line by any given filter-voltage.

If the harmonic-reduction requirements are such as to require a large filter-capacitor, having a large kva. rating, a serially connected resistor

is necessary in order to prevent, or at least reduce, the oscillations in the discharge-current of the capacitor during the commutating periods of the rectifier. These oscillations, if large enough, may produce destructive excessive voltages and may render the rectifiers unstable and short-circuit them. Said oscillations also add to the harmonic content of the anode-currents, and are reflected into the line-current. If the required size of filter-capacitor is intermediate in value, the amplitude of oscillation of an undamped discharge may be so small that it would not pay to accept the power-loss incident to adding a series resistance to the filter-capacitor, so far as the capacitor-discharge conditions are concerned.

The damping-resistance R for the parallel or A.-C. filter 40 should always have I^2R losses not exceeding 1% to 2% of the kilowatt output-rating of the rectifiers, and usually much lower resistance-losses will be involved.

However, the beneficial effect of the filter, in eliminating the higher harmonics in the transformer, will also eliminate the very substantial iron-losses which would otherwise be produced in the transformer-iron by the fluxes due to the eliminated higher harmonics, resulting in an energy-saving which may, under some conditions, equal or exceed the resistance-loss in the damping-resistance of the filter.

Instead of connecting the filter-capacitor across the two terminals S_1 and S_2 of the secondary winding, it could be connected, preferably symmetrically, across any other number of secondary-turns, thus changing the voltage of the capacitor. By symmetrical, I mean, with the mid-point of the connection coincident with the mid-tap of the secondary. There is evidence to indicate, particularly when the A.-C. filter is connected across secondary tap-connections that are symmetrical, that, due to the mutual coupling between the two secondary-halves, the inductance of the secondary winding at one end seems to be equal and opposite to the inductance of the secondary winding at the other end, so that these end-inductances apparently do not add any net inductance in the filter-circuit, over the inductance which is present when the filter-capacitor is connected directly from anode to anode.

There are certain practical limits as to the size of the A.-C. filter-capacitor C . If it is too small, it will be in parallel-resonance with the equivalent secondary inductance L of the transformer (including the primary-circuit inductance) at too high a frequency, so that the effect of adding the filter-capacitor will be to magnify or enlarge harmonics which are of a high enough order to involve rather large telephone-interference weighting factor T , thus producing a rather large increase in the telephone-interference due to the products of the harmonics in question, times the proper weighting-factor T , and this increase in interference may even be more than the decrease which results from the cutting off of still higher harmonics. In many cases, a resonant frequency of the order of the 6th or possibly the 8th harmonic may be a satisfactory optimum figure to name, particularly on a 25-cycle system. Expressed in frequencies, the C and L , as hereinabove defined, would then be optimally tuned to resonate at something of the order of 150 cycles, although possibly they might resonate at a frequency as high as 200 cycles, particularly under maximum line-current load-conditions, during acceleration.

The effective value of the equivalent secondary inductance L , or the effective supply-circuit in-

ductance up to the rectifiers, is subject to a certain amount of variation, depending upon the position of the vehicle between the successive feed-in points 2 and 3 of the trolley 1, and also dependent upon the length of feeder 4 back to the source 5. This variation in reactance may amount to anywhere from 0.2 ohm to something like 6 ohms, on a primary-voltage basis, although ordinarily the reactance-variation is not as great as this. If the reactance-variation is small enough to keep the filter-tuning well away from both the 5th and 7th harmonics (on a 25-cycle system), with an average tuning of about the 6th harmonic, this arrangement has been found to be advantageous. However, a variation in the tuning, from the 6th, through the 7th, and into the 8th harmonic, would be quite acceptable. If a sufficiently large damping resistance R is used, as will be subsequently pointed out, a much smaller filter-capacitor C may be used.

If a larger filter-capacitor C were used, tuned, say, to the 4th harmonic (in a 25-cycle system), or to a frequency of 100 cycles, the fundamental-frequency resistance-losses (in any given size of the series discharging resistance R) would be larger, being proportional to the reciprocal of the third power of the frequency-ratio of the tuned frequencies which are being compared. I consider 100 cycles, or the 4th harmonic on a 25-cycle system, the minimum resonance-frequency to which my filter-capacitor C should be tuned.

As has been indicated before, the filter-capacitor C may be tuned to a much higher frequency than 200 cycles (or the 8th harmonic on a 25-cycle system), particularly if an adequate damping resistance R is used. In general, whatever the size of the filter-capacitor C , there is an optimum value of damping resistance R . Thus if, for any given value of the filter-capacitor C , the value of the damping resistance R is varied, the inductive-interference noise-level may be plotted against the damping resistance R , and a value of R may readily be found at which the noise-level is the lowest, or at which the noise-level is decreasing so slowly, with increasing values of R , that no further increase in R would be economically justifiable. If a smaller filter-capacitor C is used, it will draw a smaller filter-current at the line-frequency (25 cycles, for example), and hence a larger value of damping resistance R may be used, without prohibitively increasing the I^2R losses in said resistance.

When the value of the damping resistance R is increased, the sharpness of the resonance at the tuning-point is decreased, so that the multiplying-factor K , at resonance, becomes much smaller, approaching unity, as will be seen from Equation 10. Consequently, with a sufficiently large damping-resistance R , the A.-C. filter 40 will not greatly increase the telephone-interference noise due to the lower-order harmonics, up to a value somewhat higher than the tuning-point, while the filter will still reduce the noise due to still higher harmonics.

It has been discovered that some of the line-harmonics which are caused by the railway-car or locomotive seem to resonate with the trolley-capacitance. In one instance, a pronounced effect of this kind has been observed at approximately 2800 cycles. My A.-C. filter 40 is quite effective in reducing this trolley-resonant harmonic, even when the filter is tuned to such a high frequency that it would otherwise seem to be of no noise-reducing value.

I have found that, when an optimum choice of

the resistance-value R is made, my A.-C. filter is effective in making some reduction in the telephone-interference noise-level when even a small filter-capacitor C is used, tuned to about the 12th harmonic on a 25-cycle system, or 300 cycles; and the evidence seems to indicate that a very much smaller capacitor would be effective, tuned to the 24th harmonic (600 cycles), or even to the 36th harmonic (900 cycles), or higher, provided that an adequately large damping-resistance R is used, in each case.

In addition to reducing the telephone-noise interference, my A.-C. filter 40, if adequately damped, also reduces or eliminates the radio-interference harmonics.

I have heretofore discussed the value of the damping resistance R from the standpoint of its critical value during the discharge of the filter-capacitor C . There is evidence that damped or partially damped charging-conditions for the filter-capacitor C may also be desirable, particularly from the standpoint of radio-interference, referring to the conditions which exist when the line-frequency voltage is again applied to the capacitor C at the end of each commutating-period of the rectifiers. During this charging-period, the effective inductance in series with the capacitor C is the equivalent combined transformer-and-line inductance L , as viewed from the secondary side of the transformer, and the critical value of the damping resistance R , during these charging conditions, is

$$R = 2\sqrt{L/C} \quad (19)$$

which is much larger than the critical damping resistance on discharge, as given in Equation 8.

I believe that the damping resistance R should have a value between the limits of the critical value on charge, and say about half of the critical value on discharge, with the higher values of damping resistance prevailing at the higher tuning-frequencies or smaller values of the capacitor C , and with the lower values of damping resistance prevailing at the lower resonance-frequencies or when a large filter-capacitor C is used.

The foregoing discussions of the secondary filter 40 have been based upon the assumption that a fixed transformation-ratio, or primary-to secondary voltage-ratio, is applicable to this filter, notwithstanding the use of the variable taps 17 to control the secondary voltage which is applicable to the anode-leads 18-19 of the rectifiers. This fixed filter-voltage ratio is usually desirable, because any change in the voltage-ratio which is applicable to the filter-capacitor C will change the resonant frequency in inverse proportion to the voltage-change. Thus, if the filter-capacitor C , when connected across the full secondary voltage of the transformer (or any other voltage), is in resonance with the transformer-inductance L at the sixth harmonic, or 150 cycles, then a change in the filter-capacitor connections, to secondary taps 17 having a voltage equal to 14% of said voltage, will change the resonant-harmonic order from 6 to $6/14 = 42.9$, and will change the resonant frequency from 150 cycles to $150/14 = 1071$ cycles, which is substantially the frequency at which the telephone-interference weighting-factor is a maximum, or $T = 12,000$ approximately. Since the filter-voltage should preferably, therefore, be fixed, it is obvious that any voltage-changing taps that are used should be on the secondary rather than the primary side of the transformer.

In practical railway-electrifications, in rectifier-

powered equipments ranging in size from the smallest multiple-unit car to the largest locomotive, the anode-to-anode running-voltage may vary from something like 300 volts to something like 1300 volts, more or less, while the equivalent secondary reactance L may vary over a range extending from something like .02 to .002 henry, more or less, depending upon the primary or line-voltage, the rating, the frequency (such as 25 or 60 cycles), and other variables. The A.-C. filter-circuit generally takes a current I_c of the order of perhaps anywhere from 1 or 2 amperes to possibly as high as 500 amperes, with perhaps a representative value around 100 amperes. The resistance-losses through the damping-resistor R are equal to $I_c^2 R$, which is subject to a rather wide range of variation, with the resistance-losses increasing rapidly as the size of the filter-capacitor C is increased, that is, as the resonant-frequency of the filter is decreased.

With my preferred amount of A.-C. filter, I save enough weight and cost in traction-motors (including the gearing), and in the transformer and the control, to more than pay for the rectifier, the filter and the associated equipment. This makes the rectifier motive-power equipment favorably competitive with all other types of electric motive-power equipments for self-propelled vehicles.

The secondary-connected filter-capacitor C of a rectifier-powered traction-motor equipment is completely discharged each half-cycle, during the commutating period when the secondary voltage is very nearly zero, being equal to the sum of the voltage-drops of two rectifiers. Hence the secondary-connected filter-capacitor C has no opportunity to build up cumulative resonance-voltages at any except the highest frequencies, which are not a problem. In this respect, the rectifier motive-power unit has a distinct advantage over alternating-current motive-power equipments such as the single-phase traction-motors, which have quite a few line-harmonics, but which cannot be equipped with filters which are discharged every half-cycle, thus requiring resonating filters to reduce the line-harmonics, these resonating filters being much heavier, and much more costly to build and maintain, than my non-resonating filter C . In this respect, the secondary connection of the filter, in a rectifier power-unit, has an advantage over the primary connection of the filter, in the same kind of rectifier power-unit, because the inductance of the transformer would be interposed between a primary-connected filter-capacitor and the short-circuited secondary terminals, during the commutating periods, so that the primary-connected capacitor would not be as effectively and completely discharged each half-cycle.

My anode-to-anode or secondary filter-capacitor C also has a very distinct advantage in at least partially counter-balancing the principal objections to the large angle of overlap which I prefer to use, these objections being the lowered power factor and the increased regulation which is produced by the large equivalent inductance L which is required in order to maintain a large angle of overlap. The filter-capacitor C draws a substantial leading current, which directly improves the power factor, and which, flowing through the large inductance L , produces an additive voltage-component to the line-voltage, thereby improving or reducing the regulation.

An important advantage of my rectifier-powered motive-system is that it works just as well,

or better, on a 60-cycle supply, than on the usual 25-cycle (or less) frequency which is common in railway-electrifications. The 60-cycle supply has many advantages, which are well known.

A very important advantage of my rectifier-powered traction-equipment is that it combines the principal advantages of both the single-phase trolley-system and the direct-current railway-system. The chief asset of the single-phase trolley-system lies in the economics resulting from its high voltage, and in its flexibility. If we increase the trolley-voltage, we reduce the inductive-interference IT values in inverse proportion to the first power of the voltage. The chief asset of the direct-current railway-system lies in the simplicity and the flexibility of voltage-control of its direct-current traction-motors. My present system combines all of these advantages.

As compared to the single-phase series-motor system, a rectifier motive-power system is lower in cost and weight, occupies less total space, has higher running-efficiencies, a higher power-factor, less standby-losses, and as small an amount of inductive interference as may be desired. I believe that the reduced maintenance of the D.-C. traction-motor and its gearing should easily more than overbalance the added maintenance of the rectifier-equipment. The direct-current motors of the rectifier-powered vehicle have much higher values of tractive-effort than any single-phase motor, and the rectifier motive-power equipment has better anti-slip features, and can be safely applied at higher adhesions, than is permissible for other types of motive-power. The net results of these tractive effort advantages means that fewer axles will be needed for a rectifier power-unit than for a single-phase motor-equipment, for a given duty-cycle, and that more horsepower per axle can be used on a rectifier-locomotive than has ever before been contemplated on any type of locomotive. Moreover, the rectifier motive-power unit can be used under a 60-cycle trolley, or it can be used interchangeably between a 25-cycle trolley-zone and a 60-cycle trolley-zone, or between an A.-C. and a D.-C. zone.

Similar advantages are to be found for the rectifier power-unit when it is compared with the motor-generator power-unit for self-propelled vehicles.

I have so far described my invention in its application to a rectifier-powered railway-vehicle, which is the first application for which my invention was designed. It will be noted that I have provided a novel rectifier-design which, in some cases, avoids inductive-interference difficulties without requiring a filter; and I have also designed a novel filter-design for connection to the secondary circuit of the transformer which energizes the harmonic-generating device from the supply-circuit which is subject to inductive interference. The general principles of my invention are susceptible of more general application, in circuits and systems other than the rectifier-powered railway-vehicle which I have thus far illustrated. Some of these more general applications of my invention are exemplified in Figs. 9, 10 and 11, which will now be described.

Fig. 9 is a view somewhat similar to Fig. 1, except that it shows my secondary filtering-device applied to a railway vehicle in which the load may be any one of a number of known kinds or embodiments of an alternating-current motor or motors 24', which do not use any rectifier.

The A.-C. railway-motor 24' is an alternating-current series commutator-motor, a known form of which is illustrated, comprising an armature 25', a serially connected interpole field-winding 26', and a serially connected reversing-switch 27' which connects the main field-winding 23' in series with the motor. These motor-circuits are energized in accordance with any suitable variable-speed control-system, which is symbolized, in Fig. 9, by having the motor-circuit energized between the secondary-terminal S2, and a variable tap 50 on the secondary winding 11 of the transformer 10.

The series alternating-current motor 24' of Fig. 9 may be regarded as being characteristic or symbolic of any load-device of a type tending to draw objectionable supply-circuit harmonics in the telephone-interference frequency-range. As previously indicated, such a motor produces a considerable amount of telephone-interference in the supply-circuits 4-1, although the intensity of the telephone-interference noise, due to A.-C. traction motors, has heretofore been less than was obtainable in any previously known rectifier-powered railway-vehicle. My untuned secondary filter-circuit 40, comprising a capacitor C and a damping resistance R, precisely as shown in Fig. 1, and with substantially the same limitations, is applicable also to A.-C.-motored railway-vehicles, as shown at 40' in Fig. 9, and when so used, it very materially reduces the noise-level of the telephone-interference caused by the harmonics which are produced in the A.-C. motor 24'.

The principles of my improved rectifier-designs, which have heretofore been described as single-phase systems, may also be applied to polyphase rectifiers, either with or without secondary filters. The application of my secondary filters to two exemplary polyphase-rectifier installations are shown in Figs. 10 and 11.

In Fig. 10, I have shown the application of my secondary filters to a three-phase rectifier-assembly 21A, 21B and 21C, which is energized from the zigzag secondary windings 110 of a polyphase transformer 90. The primary-winding phases A⁰, B⁰, C⁰, of this transformer, are energized from a polyphase supply-line 54 which is in inductive-interference coupling with respect to a communication-system 6. The secondary windings 110 comprise two separate windings for each phase, as indicated by the letters A', A'', B', B'', C' and C'', as will be obvious. The return-circuit 160 for the D.-C. load-device 51 is brought back to the star-point of the zigzag secondary winding 110, as is usual, as shown, for example, in a Bosch Patent 2,106,826 of February 1, 1938.

In Fig. 10, my secondary filter-circuits 40A, 40B and 40C are connected, in three delta phase-connections, across the respective secondary terminals 11A, 11B, and 11C, which energize the three rectifiers 21A, 21B, and 21C. During the commutating-periods of the rectifier-tubes 21A and 21B, the filter 40A is short-circuited and discharges. The other filters 40B and 40C perform in the same way during the commutating-periods for the other pairs of rectifiers.

Fig. 11 illustrates the application of my invention to a double three-phase rectifier-system of a well-known type, such as is shown, for example, in the Atherton Patent 1,979,660 of November 6, 1934. In Fig. 11, the secondary windings of the polyphase transformer 9' are connected in two three-phase stars A', B', C' and A'', B'', C'', with the two star-points connected

by an interphase transformer IT. Three of the six rectifiers, marked 21₁, 21₂ and 21₃, are connected in series with the respective terminals 11₁', 11₂', and 11₃' of the first half of the secondary windings, while the other three rectifiers, marked 22₁, 22₂, and 22₃, are connected across the respective terminals 11₁'', 11₂'', and 11₃'' of the second half of the secondary windings. The direct-current load 51 is connected between the common cathode-bus 28 and the return-conductor 16'', which goes to the midpoint of the interphase transformer IT.

In applying my secondary filters to the double three-phase rectifier-system shown in Fig. 11, three of the filters, marked 40₁', 40₂', and 40₃', are connected in delta across the anode-leads 11₁', 11₂', and 11₃' of the first group of rectifiers 21₁, 21₂ and 21₃ which are commutating, one with respect to another. Thus, during the commutation-period for the rectifiers 21₁ and 21₂, the filter 40₁' is short-circuited and discharges, and so on. In like manner, three other filters, 40₁'', 40₂'', and 40₃'', are connected in delta across the three anode-leads 11₁'', 11₂'', and 11₃'' of the other three rectifiers 22₁, 22₂, and 22₃.

In all the embodiments of my invention, the preferred design-constants and limits, governing the choice of the filter-capacitors C and the damping-resistors R, are the same as has been particularly described, in considerable detail, in connection with the application of my invention to single-phase rectifier-powered railway-vehicles. In the case of the polyphase rectifier-systems of Figs. 10 and 11, the rectifier-design, as to commutating-angles, substantially undelayed firing, and the ripple-content in the D.-C. circuit 26—16° or 23—16'', follow the principles which have been outlined in connection with the single-phase rectifier-applications of my invention.

While I have described my invention in detail, in connection with a single preferred form of embodiment, for illustrative purposes, and while I have cited specific values, and ranges of values, of the various physical constants which are preferred, or which might be used, I wish it to be understood that I am not limited, in every respect, and in every possible form of embodiment of my invention, to all of these precise details, as it is obvious that many changes may be made, by way of the substitution of equivalents, or the omission or addition of one feature or another, or the re-evaluation of certain constant, without departing from certain aspects of the essential features of my invention. I desire, therefore, that the appended claims shall be accorded the broadest construction consistent with their language.

I claim as my invention:

1. A rectifier-power transportation equipment comprising the combination, with a single-phase trolley supply-circuit which is subject to telephone-interference considerations, of a self-propelled vehicle comprising: a transformer-means having primary and secondary circuit-means; a direct-current load-means including a series direct-current traction-motor for said vehicle; a rectifier-assembly for energizing said direct-current load-means from said secondary circuit-means, said rectifier-assembly comprising a plurality of rectifier-means, the output-circuit of said rectifier-assembly being substantially free of telephone-interference considerations; connection-means for energizing said primary circuit-means from said supply-circuit, the com-

bined transformer and supply-circuit inductance being sufficient to cause the conducting periods of successively operating rectifier-means to overlap for at least about 20° during each half-cycle during maximum load-conditions; and an untuned filter-means, connected in parallel-circuit relation to the secondary circuit-means of the transformer-means and in parallel-circuit relation to successively operating rectifier-means, and comprising a capacitor and a damping resistance, said capacitor having such capacitance as to be in parallel resonance with the effective secondary-voltage-base inductance of the transformer and supply-circuit combined, at a frequency in the range between 100 and 900 cycles, during at least some operating-conditions.

2. The invention as defined in claim 1, characterized by said overlap being at least about 40°.

3. A rectifier-powered equipment comprising, in combination: an alternating-current supply-circuit which is subject to telephone-interference considerations; a transformer-means having primary and secondary circuit-means; a direct-current load-means; a rectifier-assembly for energizing said direct-current load-means from said secondary circuit-means, said rectifier-assembly comprising a plurality of rectifier-means, the output circuit of said rectifier-assembly being substantially free of telephone-interference considerations; connection-means for energizing said primary circuit-means from said supply-circuit, the combined transformer and supply-circuit inductance being sufficient to cause the conducting periods of successively operating rectifier-means to overlap for at least about 20° during each half-cycle during maximum load-conditions; and an untuned filter-means, connected in parallel-circuit relation to the secondary circuit-means of the transformer-means and in parallel-circuit relation to successively operating rectifier-means, and comprising a capacitor and a damping resistance, said capacitor having such capacitance as to be in parallel resonance with the effective secondary-voltage-base inductance of the transformer and supply-circuit combined, at a frequency in the range between 100 and 900 cycles, during at least some operating-conditions, and said damping-resistance having a value between the critical value of damping-resistance on charge and about half of the critical value of damping-resistance on discharge.

4. A rectifier-powered equipment comprising, in combination: an alternating-current supply-circuit which is subject to telephone-interference considerations; a transformer-means having primary and secondary circuit-means; a direct-current load-means; a rectifier-assembly for energizing said direct-current load-means from said secondary circuit-means, said rectifier-assembly comprising a plurality of rectifier-means, the output-circuit of said rectifier-assembly being substantially free of telephone-interference considerations; connection-means for energizing said primary circuit-means from said supply-circuit, the combined transformer and supply-circuit inductance being sufficient to cause the conducting periods of successively operating rectifier-means to overlap for at least about 20° during each half-cycle during maximum load-conditions; and an untuned filter means, connected in parallel-circuit relation to the secondary circuit-means of the transformer-means and in parallel-circuit relation to successively operating rectifier-means, and comprising a capacitor and a damping resistance, said capacitor being large

enough to draw a current of at least an ampere, and the I^2R loss in the damping resistance being less than 2% of the continuous rating of the load-means.

5. The invention as defined in claim 4, characterized by said overlap being at least about 40° .

6. A rectifier-powered equipment comprising, in combination: an alternating-current supply-circuit which is subject to telephone-interference considerations; a transformer-means having primary and secondary circuit-means; a direct-current load-means; a rectifier-assembly for energizing said direct-current load-means from said secondary circuit-means, said rectifier-assembly comprising a plurality of rectifier-means, each becoming conductive when its impressed voltage reaches a relatively small value in its conductive polarity; connection-means for energizing said primary circuit-means from said supply-circuit; an untuned filter, connected in parallel-circuit relation to the secondary circuit-means of the transformer, and comprising a capacitor and a damping resistance; and a tuned filter connected in shunt-circuit relation to at least some portion of the load-means.

7. A rectifier-powered transportation equipment comprising the combination, with a single-phase trolley supply-circuit which is subject to telephone-interference considerations, of a self-propelled vehicle comprising: a transformer having a primary circuit and a secondary circuit; a series direct-current traction-motor for said vehicle; a rectifier-assembly for energizing said direct-current motor from said secondary circuit, said rectifier-assembly comprising a plurality of rectifier-means, each becoming conductive when its impressed voltage reaches a relatively small value in its conductive polarity; and connection-means for energizing said primary circuit from said supply-circuit, the combined transformer and supply-circuit inductance being sufficient to cause the conducting periods of successively operating rectifier-means to overlap for at least about 20° during each half-cycle during maximum short-time load-conditions.

8. The invention as defined in claim 7, characterized by said rectifier-assembly comprising at least two single-phase rectifying devices of a type which becomes substantially non-conducting, after a conducting period, only in response to a current-decrease to substantially zero.

9. The invention as defined in claim 7, characterized by said overlap being at least about 40° .

10. A rectifier-powered transportation-equipment comprising the combination, with a single-phase trolley supply-circuit which is subject to telephone-interference considerations, of a self-propelled vehicle comprising: a transformer having a primary circuit and a secondary circuit; a series direct-current traction-motor for said vehicle; a rectifier-assembly for energizing said direct-current motor from said secondary circuit, the output-circuit of said rectifier-assembly being substantially free of telephone-interference considerations and having a total inductance which is sufficiently small to permit at least a 20% ripple to be present in some part of said circuit during maximum short-time load-conditions, said rectifier-assembly comprising a plurality of rectifier-means, each becoming conductive when its impressed voltage reaches a relatively small value in its conductive polarity; and connection-means for energizing said primary circuit from said supply-circuit, the combined transformer and supply-circuit inductance be-

ing sufficient to cause the conducting periods of successively operating rectifier-means to overlap for at least about 20° during each half-cycle during maximum short-time load-conditions.

11. The invention as defined in claim 10, characterized by said rectifier-assembly comprising at least two single-phase rectifying devices of a type which becomes substantially non-conducting, after a conducting period, only in response to a current-decrease to substantially zero.

12. The invention as defined in claim 10, characterized by said overlap being at least about 40° .

13. A rectifier-powered transportation-equipment comprising the combination, with a single-phase trolley supply-circuit which is subject to telephone-interference considerations, of a self-propelled vehicle including: a transformer having a primary circuit and a secondary circuit; a series direct-current traction-motor for said vehicle; a rectifier-assembly for energizing said direct-current motor from said secondary circuit, the output-circuit of said rectifier-assembly being substantially free of telephone-interference considerations and having a total inductance which is sufficiently small to permit at least a 25% ripple to be present in some part of said circuit during maximum short-time load-conditions, said rectifier-assembly comprising a plurality of rectifier-means, each becoming conductive when its impressed voltage reaches a relatively small value in its conductive polarity; and connection-means for energizing said primary circuit from said supply-circuit, the combined transformer and supply-circuit inductance being sufficient to cause the conducting periods of successively operating rectifier-means to overlap for at least about 20° during each half-cycle during maximum short-time load-conditions.

14. The invention as defined in claim 13, characterized by said rectifier-assembly comprising at least two single-phase rectifying devices of a type which becomes substantially non-conducting, after a conducting period, only in response to a current-decrease to substantially zero.

15. The invention as defined in claim 13, in combination with a harmonic-reducing filter connected in shunt-circuit relation to at least some portion of the motor-means, said filter having a greater shunting-effect on harmonic currents than on currents of the fundamental frequency.

16. The invention as defined in claim 13, in combination with a second-harmonic filter connected in shunt-circuit relation to at least some portion of the motor-means.

17. The invention as defined in claim 13, characterized by said overlap being at least about 40° .

18. In combination: a single-phase supply-circuit which is subject to telephone-interference considerations; a transformer having a primary circuit and a secondary circuit; connection-means for energizing said primary circuit from said supply-circuit; a load-means energized from said secondary circuit and being of a type tending to draw objectionable supply-circuit harmonics in the telephone-interference frequency-range, said secondary circuit and load-means being otherwise substantially free of telephone-interference considerations; and an untuned filter; connected in parallel-circuit relation to the secondary circuit of the transformer, and comprising a capacitor and a damping resistance, said capacitor having such capacitance as to be in parallel resonance with the effective secondary-

voltage base inductance of the transformer and supply-circuit combined, at a frequency in the range between 100 and 900 cycles, during at least some operating-conditions, and said damping-resistance having a value between the critical value of damping-resistance on charge and about half of the critical value of damping-resistance on discharge.

19. A rectifier-powered transportation-equipment comprising the combination, with a single-phase trolley supply-circuit which is subject to telephone-interference considerations, of a self-propelled vehicle comprising: a transformer having a primary circuit and a secondary circuit; a series direct-current traction-motor for said vehicle; a rectifier-assembly for energizing said direct-current motor from said secondary circuit, said rectifier-assembly comprising a plurality of rectifier-means, each becoming conductive when its impressed voltage reaches a relatively small value in its conductive polarity; connection-means for energizing said primary circuit from said supply-circuit, the combined transformer and supply-circuit inductance being sufficient to cause the conducting periods of successively operating rectifier-means to overlap for at least about 20° during each half-cycle during maximum short-time load-conditions; and an untuned filter, connected in parallel-circuit relation to the secondary circuit of the transformer, and comprising a capacitor and a damping resistance.

20. The invention as defined in claim 19, characterized by said overlap being at least about 40°.

21. A rectifier-powered transportation-equipment comprising the combination, with a single-phase trolley supply-circuit which is subject to telephone-interference considerations, of a self-propelled vehicle comprising: a transformer having a primary circuit and a secondary circuit; a series direct-current traction-motor for said vehicle; a rectifier-assembly for energizing said direct-current motor from said secondary circuit, said rectifier-assembly comprising a plurality of rectifier-means, each becoming conductive when its impressed voltage reaches a relatively small value in its conductive polarity; connection-means for energizing said primary circuit from said supply-circuit; an untuned filter, connected in parallel-circuit relation to the secondary circuit of the transformer, and comprising a capacitor and a damping resistance; and a harmonic-reducing filter connected in shunt-circuit relation to at least some portion of the motor-means, said filter having a greater shunting-effect on harmonic currents than on currents of the fundamental frequency.

22. A rectifier-powered equipment, comprising, in combination, a direct-current load-means, a rectifier-assembly comprising at least two single-

phase rectifying devices of a type which becomes substantially non-conducting, after a conducting period, only in response to a current-decrease to substantially zero; a pair of single-phase power-supply leads, connected to said two rectifying devices, respectively, at rectifying-device terminals of one polarity; and circuit-means for connecting the other terminals of said two rectifying devices to one terminal of said direct-current load-means; the supply-circuit inductance, up to said first-mentioned terminals of said two rectifying devices, being sufficient to cause the conducting periods of said two rectifying devices to overlap for at least about 20° during each half-cycle during maximum short-time load-conditions, in combination with an untuned parallel-resonant filter, connected in parallel-circuit relation across said power-supply leads, with at least a substantial part of said supply-circuit inductance on the power-supply side of said parallel-filter connection, said parallel-resonant filter comprising a capacitor and a damping resistance, said capacitor having such capacitance as to be in parallel resonance with the supply-circuit inductance as seen from the terminals of said parallel-resonant filter, at a frequency in the range between 100 and 900 cycles, during at least some operating-conditions.

23. The invention as defined in claim 22, characterized by said overlap being at least about 40°.

24. The invention as defined in claim 22, characterized by the direct-current load-circuit having a total inductance which is sufficiently small to permit at least a 20% ripple to be present in some part of said direct-current load-circuit during maximum short-time load-conditions.

25. The invention as defined in claim 22, characterized by the direct-current load-circuit having a total inductance which is sufficiently small to permit at least a 25% ripple to be present in some part of said direct-current load-circuit during maximum short-time load-conditions.
